HARALD E. ULLICH, OF LARCHMONT, WALTER E. ULLICH, OF NEW YORK, AND RUDOLPH RIETHEIMER, OF RICHMOND HILL, NEW YORK, ASSIGNEES TO H. P. ULLICH & CO., OF NEW YORK, N. Y., A CORPORATION OF NEW YORK.

NECKTIE-DISPLAY CARD.

Application filed February 4, 1926. Serial No. 85,960.

Our invention has for its object the provision of means for retaining neckties in position in their boxes or upon display cards.

Many neckties are sold to purchasers who intend to make gifts of them at holiday times, and in such cases it is customary to deliver a single tie in a box of the type generally known as a necktie box, which is usually something more than a quarter the length of the tie in length, and wide enough to take the widest part of the tie, and about half an inch deep. If ties are simply folded in the usual manner and placed in these boxes, they naturally slide around and become disarranged and wrinkled; and it has therefore been customary to employ a display card, upon which part of the tie can be placed, the rest of the tie being folded over one end and laid in back of the card. This serves in a measure to keep the tie from sliding around, but does not effectively prevent wrinkling; and consequently attempts have been made to hold the tie in place upon the card by other means, such as cutting a pair of parallel slits or openings transversely of the card so that the portion of the card between the slits may be raised, and the tie held upon the balance of the card by the transverse strip so formed, under which the tie is inserted.

Whatever means is used, it is essential that such means shall be simple, in order that time may not be lost in putting the ties in the boxes; but while these plans heretofore used have been simple, they have failed of effectiveness.

Accordingly we have devised a novel and effective method of fastening the tie upon the display card, and our invention consists in the construction, combination and arrangement of parts herein described and claimed, and illustrated in the accompanying drawings.

In these drawings, in which similar reference characters designate corresponding parts in all views:

Figure 1 shows a necktie box having therein a display card embodying our invention, and having a tie applied thereto;

Fig. 2 is a front elevation of the display card;

Fig. 3 is a view of the display card shown

in Fig. 2 from the back, upside down, showing how the tie is applied thereto; and, 55

Fig. 4 is a section through the display card and tie taken approximately on the line 4—4 of Fig. 1.

Referring to these drawings, in Fig. 1 we have shown a necktie box 1 having the cover 2 removed and placed on the bottom of the box in the usual manner for display purposes, in which box is disposed a display card 3 upon which the necktie 4 has been mounted and is securely held as desired centrally in the box. 60

As shown in Fig. 2, there are three features of the card 3 embodying our invention, each of which may be used separately, or in conjunction with one or both of the others; although in its preferred embodiment all three features are used, and are shown in Fig. 2; namely, first, means for definitely fixing the position of the tie upon the card and preventing longitudinal movement thereof; second, a notch, preferably at the top of the card, providing space for part of the tie to be folded over and placed behind the card; and third, means on the face of the card for holding the front of the tie in position upon the card, and especially for preventing lateral movement thereof. 70

The means for attaining the first objective, namely, that of preventing longitudinal movement of the tie, and fixing the position of the tie upon the card, consists of a tongue 5 formed in the lower part of the card by suitable slits therein. Preferably one slit 6 is placed centrally at right-angles 75

to the axis of the card and is wide enough to accommodate the thickness of a tie, and long enough to accommodate the width of a tie at the neck-band portion thereof, the other slit 7 being also wide and long enough 80 to accommodate the material of the tie, and being disposed angularly if desired as shown in Fig. 2. The tongue 5 preferably projects laterally beyond the point where the tie will engage it, and is provided with 85 suitable means such as a shoulder or an arrow-head 8 to prevent the tie, once it has been placed upon the tongue, from sliding off the same.

The second means is simply the notch or recess 9 at the top of the card, sufficiently deep 90

to permit of the tie being passed over the same without injury to the material thereof; and yet not so deep but what there will be some frictional contact upon the tie to prevent possible sliding thereof.

The third means, for retaining the tie upon the face of the card, comprise a pair of tongues 10—11, formed by slitting the card, these tongues being supported by the 10 card from material near the edges thereof, and projecting inwardly to the center of the card. To facilitate the application of the tie to the card, it is desirable to cut away at the same time that these tongues 15 are formed the portions 12—13 of the card, leaving, however, the portions 14 so that if the card is used for a narrow tie the central openings will not extend laterally far enough to show. The slits forming the tongues, however, are carried to the 20 bases of the tongues, so that a tie may be inserted wider than the portions removed.

It is desirable that the face of the card be 25 ornamented by a suitable border line 15, and that the central portion having the retaining tongues be likewise ornamented, for instance by another line 16 similar to the border, as shown; and the tongues 10—11 themselves may carry a suitable legend such 30 as the term "Season's Greetings."

The operation of the device is simple and is clearly shown by reference to Figures 3 and 4. A tie may readily be applied to the card by holding the card 3 in the right hand 35 upside down and with the back up as shown in Fig. 3, and taking the necktie 4 in the left hand, the tie being simply folded in half in the usual manner, and looping the neckband portion of the tie over the tongue 5, letting 40 the tie hang down upon the back of the card as shown in Fig. 3 and resting against the notch 9. The card may then be taken hold of with the left hand near the notch 9, the fingers resting also upon the tie and holding 45 it against the back of the card, and the card then turned to the position shown in Fig. 2. The front of the tie may then be taken about 50 at its middle point in the right hand and inserted under the left hand tongue 10 which may easily be raised with a finger of the left hand; and then holding the tie in this 55 position at the tongue with the left hand the right-hand tongue 11 may be pressed upward or forward from below with a finger of the right hand and the tie permitted to slide thereunder, so that the tie is then in position upon the card as shown in Fig. 1, and the card 3 may be inserted in a box 1 as shown in Fig. 1, if desired, or the tie may be

handled upon the card alone for display purposes. It will be noted that while the tongues 10—11 upon the face of the tie hold the front portion of the tie upon the card, so far as lateral disarrangement is concerned, the possibility is also precluded of the tie 60 slipping down when the box is tilted upward for display purposes, since the neckband of the tie is firmly hooked upon the tongue 5.

Another and simple method of securing the tie under the lateral tongues 10, 11 is to 70 grasp the card between the thumb and a finger placed at the edges of the card opposite the tongues, and exerting a pressure upon the edges of the card, pushing them toward each other at the back of the card, 75 which causes the tongues upon the face of the card to open and spread apart far enough to permit the tie to be inserted, whereupon the edges of the card are released and the tongues grip the tie.

It might also be remarked that the tie when in position effectively conceals the tongue 5; and if a tie happens to be too short to cover the tongue 5 when the tie is folded in half, this can be adjusted by folding the tie so that the front portion is longer than the back.

Having now described our invention we claim, and desire to secure by United States Letters Patent:

1. A necktie display card upon which a tie is adapted to be displayed by throwing the neckband portion of the tie over an end of the card to the back thereof, comprising a laterally projecting tongue formed in the 95 card arranged to engage said neckband portion and prevent the tie from slipping down when the card is tilted, and means for holding the tie in position laterally upon the face of the card.

2. A necktie display card upon which a tie is adapted to be displayed by throwing the neckband portion of the tie over an end of the card to the back thereof, comprising a laterally projecting tongue formed in the 100 card arranged to engage and hold said neckband portion, a notch at the top of the card over which the tie may be passed, and opposed inwardly projecting lateral tongues formed in said card and arranged to be 105 raised to permit insertion of the tie to be held thereunder against lateral displacement.

In testimony whereof we have signed our names to this specification.
